UNITED STATES PATENT OFFICE.

JUSTO ALVAREZ, OF FLUSHING, NEW YORK.

SHOE LACE.

Application filed December 4, 1922. Serial No. 604,852.

To all whom it may concern:

Be it known that I, JUSTO ALVAREZ, a citizen of Spain, residing at Flushing, in the county of Queens and State of New York, have invented new and useful Improvements in Shoe Laces, of which the following is a specification.

My present invention relates to shoe laces and has for its object to provide a lace of peculiar and advantageous construction, susceptible of being applied to a shoe in such manner that it is very easy to fasten or unfasten the lace quickly, and the lace is not liable to render a shoe uncomfortable or to detract in any measure from the finished appearance of a shoe.

To the attainment of the foregoing, the invention consists in the improvement as hereinafter described and definitely claimed.

20 In the accompanying drawings, forming part of this specification:—

Figure 1 is a view showing the application of my novel lace to a shoe.

Figure 2 is a view of the lace per se.

25 Figure 3 is an enlarged diametrical section showing my improvement on one end of the lace.

Similar numerals of reference designate corresponding parts in all of the views of the drawings.

The lace 1 is preferably, though not necessarily, of round type and is provided on one of its ends with a tip member 2 or is otherwise equipped to facilitate its insertion 35 through the eyelets of a shoe. At its opposite end the lace is provided with a button best shown in Figure 3 and which constitutes the salient feature of my invention. The said button is made up of a small metallic disk 3 and a small metallic disk 4. These disks are of circular form, and the disk 3 is provided with a peripheral 40 fastening flange 5. The disk 4 has at its inner side a small round tube 6 adapted to receive and when properly clamped to hold any kind of shoe lace. After the end portion of the shoe lace is secured in the tube 6, the metallic disk 3 is applied to the outer side of the metallic disk 4, and the flange 5 45 is fastened over the peripheral portion of the disk 3, when the disk 3 will be strongly connected to the disk 4, and the lace will be permanently connected to the two disks.

In this connection it will be noted that one end portion of the lace is frayed, and is 55 housed and secured between the two disks, Figure 3. This manifestly lends strength to the connection of the button to the lace, and at the same time completely encloses and protects the frayed end of the lace. 60

As will be understood from Figure 1 of the drawings the button formed by the connected disks 3 and 4 in the manner described in the foregoing, is placed in the upper eyelet at the inside of a shoe, and the end of the string is passed through the lower eyelet from the outer side of the shoe. From this it follows that it is extremely easy to fasten or unfasten the lace expeditiously, and it will also be noticed that the lace is not 70 liable to subject the wearer to discomfort, and when the lace is properly used the shoe will be free of knots or visible string ends.

I have entered into a detailed description of the construction and relative arrangement of the parts embraced in the present and preferred embodiment of my invention in order to impart a full, clear and exact understanding of the said embodiment. I do not desire, however, to be understood as 75 confining myself to the specific construction and relative arrangement of parts inasmuch as in the future practice of the invention various changes and modifications may be made such as fall within the scope of my 80 invention as defined in my appended claim. 85

Having described my invention, what I claim and desire to secure by Letters Patent, is:—

A shoe lace having at one end a frayed portion and a button made up of two metallic disks, one of the disks being apertured and provided with a lateral central tube receiving a part of the lace, and the other disk being applied to the side of the first-named disk and the said end portion of the lace being frayed and housed between the disks, remote from the tube and being provided with a circumferential fastening flange straddling the peripheral portion of the first-named disk whereby the disks are connected together and the lace is permanently secured to the disks. 95 100

In testimony whereof I affix my signature.

JUSTO ALVAREZ.
